UNITED STATES PATENT OFFICE.

SAMUEL HASKELL, OF NEW YORK, N. Y., ASSIGNOR TO FAIR AND CARNIVAL TRADING CO. INC., OF NEW YORK, N. Y., A CORPORATION OF NEW YORK.

DOLL-MOLD.

1,154,247.

Specification of Letters Patent. Patented Sept. 21, 1915.

Application filed September 14, 1914. Serial No. 861,533.

To all whom it may concern:

Be it known that I, SAMUEL HASKELL, a subject of the Czar of Russia, residing at New York city, Manhattan borough, county 5 and State of New York, have invented certain new and useful Improvements in Doll-Molds, of which the following is a full, clear, and exact description.

This invention relates to an improvement 10 in molds, particularly designed for molding or forming the bodies of dolls.

In carrying my invention into practice I provide a mold consisting of a plurality of separably connected sections or members 15 (preferably three), two of the members being adapted for engagement one with the other, the third member being held in position by the other two mold-members.

I will now proceed to describe my invention in detail, the novel features of which I 20 will point out in the appended claims, reference being had to the accompanying drawings, forming part hereof, wherein:—

Figure 1 is a front view, slightly in perspective, of my improved mold; Fig. 2 is a side elevation of one of the body-members thereof; Fig. 3 is an enlarged sectional view of the upper portion of the mold, showing the shoulder section in position; Fig. 4 is 30 a sectional plan view taken on a line 4—4 in Fig. 3, showing the shoulder section and one of the body sections; Fig. 5 is a top plan view of the assembled mold; Fig. 6 is a sectional plan view, the section being taken on a line 6—6 in Fig. 1.

As herein illustrated, my improved mold consists of a plurality of body-members 1 and 2 and a shoulder section 3 supported thereby when the body sections are assembled. The mold-members may be made out 40 of any suitable material, preferably aluminum. To facilitate the parting or separation of the molds, I preferably split the same diagonally as at 5 and 6, the mold-members 45 being suitably braced by ribs 7. Each mold-member is provided with a core-print 8 for the arm-holes and a core-print 9 for the openings for the legs. In this instance the mold-member or body-member 1 is provided 50 with locking lugs 10 adapted to enter sockets 11 in the body-member 2. The body-member 1 is provided with a concaved wall 12, and the body-member 2 with a concaved wall 13 to form an opening 14, in the top of 55 the mold, through which the material for

the doll body is poured, the said material being plastic.

The body-member 1 is provided with an annular shoulder 15 adjacent to the upper end thereof, as is the body-member 2 with 60 a similar shoulder 16, the said shoulders taking a curved course over the arm-hole core-prints 8, as at 17 (Fig. 2) to strengthen the wall of the body portions at the points adjacent said core-prints. To mold the 65 shoulders, as well as to core the opening for the head, I provide the mold-member 3, as shown in Fig. 3, the said shoulder-member being provided with a core-print 18 having an opening 19 therein for the passage of the 70 material to be molded. As can be seen in Fig. 3, the mold-member 3 rests upon the shoulders 15 and 16 along its bottom edge 20. The rounded surface 21 of the shoulder mold-member 3 rests in contact with 75 the rounded surface 22 of each mold-member 1 and 2.

When the mold-members 1 and 2 are placed together, as shown in Fig. 1 (the mold-member 3 being positioned as shown in Fig. 3) the said mold-members 1 and 2 will firmly hold the mold-member 3 in position, the lugs 10 and recesses 11 holding the mold-members 1 and 2 in alinement. In order 80 to accurately fit the member 3 to the members 1 and 2, I provide the said member 3 with a rib 23 curved to conform to the shape of the divisional line of the mold-members, the curved surfaces 21 meeting at the rib 23. 85

As can be seen in Fig. 5, the curved wall 90 12 of the body-member 1 is coincident with the wall of the opening 14, as is the curved wall 13 of the body-member 2.

As can be seen in Fig. 3, the opening 19 in the mold-member 3 is funnel-shaped, the 95 upper edge meeting the lower edge of the walls 12 and 13 of the body-members 1 and 2.

Having now described my invention, what I claim and desire to secure by Letters Patent is:

1. A mold for doll-bodies, consisting of a plurality of body-members, a projection carried by each body-member adjacent one end thereof, said projections being adapted to 100 aline and form a support when said mold-members are assembled, and a one-piece shoulder-member supported by said projections. 105

2. A mold for doll-bodies consisting of a 110

- plurality of body-members, provided at the upper ends thereof with a curved wall, a projection carried by each body-member adjacent the curved wall carried thereby, and 5 a one-piece shoulder-member supported by said projections, said shoulder-member having a curved top surface adapted to engage the curved walls carried by the body-members.
10. 3. A mold for doll-bodies consisting of a plurality of body-members, provided at the upper ends thereof with a curved wall, a projection carried by each body-member adjacent the curved wall carried thereby, a

one-piece shoulder-member supported by 15 said projections, said shoulder-member having a curved top surface adapted to engage the curved walls carried by the body-members and a core-print carried by said shoulder-section, provided with a central opening 20 adapted to form a head-opening in the doll-body.

Signed at New York city, N. Y., this 11th day of September, 1914.

SAMUEL HASKELL.
